Primary Examiner — Jae Liang*Assistant Examiner* — Riya Salil Kamat(57) **CLAIM**

The ornamental design for a sport ball slinger as shown and described.

DESCRIPTION

FIG. 1 is a front view of a sport ball slinger showing my new design;

FIG. 2 is a rear view of the sport ball slinger;

FIG. 3 is a right side view of the sport ball slinger;

FIG. 4 is a left side view of the sport ball slinger;

FIG. 5 is a top view of the sport ball slinger;

FIG. 6 is a bottom view of the sport ball slinger;

FIG. 7 is a top front side perspective view of the sport ball slinger; and,

FIG. 8 is a top front side view of the sport ball slinger in use. The broken lines in FIG. 8 are illustrative of environmental structure forming no part of the claimed design.
